FORM FOR CONTINUOUS CONCRETE PIPE

Gustaf L. Carlson, Turlock, Calif.

Application September 4, 1935, Serial No. 39,169

2 Claims. (Cl. 25—128)

This invention relates to a form for constructing the upper half of a continuous concrete pipe, the general object of the invention being to so construct the form that it can be readily removed from one end of the pipe or a completed section thereof from the exterior of the pipe and without necessitating the workmen crawling into the pipe, thus permitting the pipe to be constructed of such diameter as to be too small for a workman to enter the same.

This invention also consists in certain other features of construction and in the combination and arrangement of the several parts to be hereinafter fully described, illustrated in the accompanying drawings and specifically pointed out in the appended claims.

Figure 1 is a longitudinal view showing the improved form in position in a lower half of a concrete pipe ready to receive the concrete for the upper half.

Figure 2 is a vertical sectional view through that section of the form which is located at the completed end of the pipe.

Figure 3 is a section on line 3—3 of Figure 2.

Figure 4 is a section on line 4—4 of Figure 2.

Figure 5 is a section on line 5—5 of Figure 2.

Figure 6 is a view of the hook.

In these drawings, the numeral 1 indicates a plurality of form sections, each of which is substantially of semi-circular form in cross-section and has a reduced lip forming part 2 at one end for receiving the adjacent end of the next section so that when the sections are placed together, they will form a continuous and unbroken exterior surface for the concrete, it being understood that these forms are used for completing the upper half of a concrete pipe, as shown in Figure 1. Each section 1 has a sectional cross-bar 6 adjacent each end thereof, the inner end of the two sections being pivoted together as shown at 7, and their outer ends are pivoted to the inward flanges 8 of the sections as shown in Figure 4, at 9.

A longitudinally extending bar 10 connects each pair of cross-bars 6 together and the ends of the bar 10 may be connected with the cross-bars by the pivots 7. An upright 11 is placed in the front portion of each section and is formed of two sections adjustably connected together as shown at 12 so that the length of the upright can be adjusted and the upper portion of the lower section is pivoted to the front end of a bar 10 as shown at 13. A shoe 14 is pivoted to the lower end of each upright and rests upon the bottom of the lower half of the pipe as shown in Figure 1. The upper end of the upright is bent rearwardly and passes

through an eye 16 depending from the top of the section.

An upright 18 is placed at the rear end of the last section and is also adjustable as to its length as shown at 19 and the upper end of this upright is pivoted or hinged to the top of the rear section, as shown at 20. This upright also has a shoe 21 at its lower end for resting on the bottom of the completed half construction of the pipe and a pulley 22 is carried by the forwardly extending ears 23 of the upper portion of the upright.

As will be understood, when the cross-pieces 6 are straight the form will be held expanded and will be supported in this position by the uprights and in position to receive the concrete for the upper half of the pipe.

A cable 24 is passed around the pulley 22 with both ends of the cable extending from the outermost form section, as shown in Figure 1 and one end of the cable has a snap hook 25 attached thereto for engagement with a hook 26 to which a second cable 27 is connected. These parts are arranged as shown in Figure 1 and after the concrete has formed the upper half of a pipe or a section thereof, and it is desired to remove the form sections, the lower part of the cable 24 is pulled upon so that the hook 26, which is formed as shown in Figure 6, will pass through the opening 28 formed in the upper part of the upright 11. Then the cable 27 is pulled upon, which will cause the hook to catch in the wall of the eye 28 and thus the first upright 11 will be pulled forwardly to remove the part 15 out of the eye 16 and also to exert a pull upon the bar 10 which will break the cross-pieces 6 of the outer section so that such section will contract and thus this section can be removed from the pipe. After this is done, the cable is again pulled upon to place the hook 26 in engagement with the front upright of the next section and the cable 27 is pulled upon to pull this section out of the pipe and this operation is continued until all the sections have been pulled from the pipe, the upright 18 swinging on the hinge 20 when both parts of the cable 24 are pulled upon so that it will be removed with the last form section.

Thus it will be seen that with this invention, pipes can be constructed of such a diameter that would be too small for a workman to enter the same and as far as I am aware concrete pipes have not hitherto been formed in the place they are to occupy, of a less diameter than that which will permit a workman to enter the pipe to remove the form.

It is thought from the foregoing description 55

that the advantages and novel features of the invention will be readily apparent.

It is to be understood that changes may be made in the construction and in the combination and arrangement of the several parts provided that such changes fall within the scope of the appended claims.

What is claimed is:

1. A form for the upper half of a concrete pipe, comprising a plurality of sections, cross bars in each section adjacent the ends thereof, each cross bar being formed of two sections having their inner ends pivoted together and their outer ends pivoted to parts of the sections, a longitudinally extending bar connecting the pivot point of each pair of cross bars together, an upright at the front end of each section to which the front end of the longitudinally extending bar is pivoted, a pulley carrying member pivotally connected at its upper end with the rear end of the rear section and having a pulley thereon, eyes formed in the uprights, a cable having a hook connected therewith passing through the eyes and over the pulley, both ends of the cable extending from the outer end of the pipe, said hook being constructed and arranged to permit the same to pass through the eye when the lower flight of the cable is pulled and to prevent the hook from returning through the eye when the upper flight is pulled.

2. A form for the upper half of a concrete pipe, comprising a plurality of sections, cross bars in each section adjacent the ends thereof, each cross bar being formed of two sections having their inner ends pivoted together and their outer ends pivoted to parts of the sections, a longitudinally extending bar connecting the pivot point of each pair of cross bars together, an upright at the front end of each section to which the front end of the longitudinally extending bar is pivoted, a pulley carrying member pivotally connected at its upper end with the rear end of the rear section and having a pulley thereon, eyes formed in the uprights, a cable having a hook connected therewith passing through the eyes and over the pulley, both ends of the cable extending from the outer end of the pipe, said hook being constructed and arranged to permit the same to pass through the eye when the lower flight of the cable is pulled and to prevent the hook from returning through the eye when the upper flight is pulled, said uprights and the pulley carrying member being adjustable lengthwise and each having a shoe at its lower end for resting upon the bottom of the lower half of the pipe and the uprights having bent portions at their upper ends engaging eyes depending from the top parts of the form sections. 5 10 15 20 25
